UNITED STATES PATENT OFFICE.

PETER S. LEKAS, OF PORTLAND, OREGON.

MATCH-SAFE.

1,208,991.

Specification of Letters Patent. Patented Dec. 19, 1916.

Application filed October 5, 1915. Serial No. 54,133.

To all whom it may concern:

Be it known that I, PETER S. LEKAS, a citizen of the United States, residing at Portland, in the county of Multnomah and State of Oregon, have invented certain new and useful Improvements in Match-Safes, of which the following is a specification.

This invention relates to the class of special receptacles and packages, and more 10 specifically to improvements in match safes.

The object of my invention is to provide a match safe having a feed and lighting arrangement whereby every match withdrawn will automatically be lighted as it is withdrawn. Persons will therefore not be able 15 to fill their pockets with matches from this safe.

My safe is not only simple and economical in construction and operation, but enforces 20 such a saving in matches that for cigar stands it is much cheaper than the devices which remain lighted constantly.

Other objects of this invention not at this time more particularly enumerated, will be 25 clearly understood from the detailed description and drawings forming a part of this specification.

Furthermore, this invention consists in the novel arrangements and combination of 30 parts more particularly described in the following specification and embodied in the claims appended hereunto and forming a part of a part of this application.

Referring now to the drawings, which are 35 merely illustrative of my invention, Figure 1 is a perspective view of my improved match safe. Fig. 2 is a vertical longitudinal sectional view taken on the line 2—2 of Fig. 1. Fig. 3 is a vertical transverse sectional view taken on the line 3—3 of Fig. 2. Fig. 4 is a detail perspective view of the 40 spring arrangement for the follower plate.

Referring further to the drawings, wherein 45 similar reference characters designate similar parts throughout the respective views, 1 designates a base plate upon which is mounted a supporting block 2 having an inclined top. A channel guide member 3 is secured upon the upper face of said block 50 and along the length thereof.

A casing 4, adapted to register with the upper face of said block, is provided with oppositely disposed flanges 5 upon the under face thereof, said flanges being adapted to 55 slidably engage with the channel guide mem-

ber 3. The front face 4^a of said casing projects upwardly a certain distance above the body portion of the casing. said front face is formed with a vertical slot 6 centrally therethrough. A cover 7 is hingedly mounted upon said casing, the forward end of said cover being formed with an upturned portion 8 which, when the cover is closed, will be in spaced apart relation with respect to the upper end of the front face 4^a.

A roll of igniting paper 9 is mounted upon a bearing 10 secured to the upper end of the front face 4^a of the casing. A strip of said igniting paper is adapted to pass between a guide member 11 secured upon one side of the upwardly projecting ends of said front face 4^a and said cover, between said ends and around a T-shaped guide member 12 mounted upon the other side, thence between said ends and to a point adjacent the outer side of the upturned portion 8, where it is secured by a clip 13. Catches 14 are mounted upon said cover and are adapted to engage with lugs 15 upon the side of the casing 4.

A match container 16, is adapted to fit within the casing and be supported in raised position above the bottom thereof by supports 17 mounted upon the inside of said casing. A slot 18 is formed in the front face 85 of the container, said slot being adapted to register with the slot 6 in said casing. The bottom of said container is cut away at 19 a certain distance inwardly from the front face thereof. Horizontal slots 20 are formed in the sides of said container near the upper edge thereof, and extend to a point near the front face of said container. A member 21, forming a false back for said container, is provided with outwardly extending flanges 95 at the upper end thereof, said flanges being adapted to slidably engage with the slots 20.

A rectangular metallic strip 22, one arm of which forms the top of said container, while the other arm forms the back thereof, is provided with a leaf spring 23 secured at one end to said back, and having a pusher member 24 mounted upon the other end thereof.

A lift handle 25 is slidably mounted within the slots 6 and 18 in said casing and container, respectively, said handle having a plate member 26 mounted transversely upon the inner end thereof. Coil springs 27 are mounted upon both sides of said plate mem-

ber, one end of each of said springs being secured thereto while the other end is secured to the bottom of said casing. Said plate member is adapted to register with the cut away portion 19 in the bottom of said container. A follower plate 28 is mounted upon coil springs 29 in such manner as to abut the under face of said plate member 26 when the handle 25 is in inoperative position and to abut the under face of said container when said handle is raised, thereby closing the cut away portion 19 to prevent the matches 30 from dropping through the opening while the handle is raised.

From the foregoing description it is obvious that when the match container is filled or partially filled with matches, the false back 21 will be maintained in compression against said matches by the spring actuated pusher member 24, thereby keeping matches toward the front end of the container. As the handle 25 is raised, the plate member 26 will engage with the lower ends of the first row of matches and force them upwardly through the opening between the upper end of the front face 4^a of the casing and the upturned end 8 of the cover. As the stem of the matches project through said opening one of them may be grasped and withdrawn, whereupon the frictional engagement of the head of the match with the igniting paper will ignite said match.

The utility, adaptability, and advantages of my improved form of match safe being obvious, it is unnecessary to further enlarge upon the same herein.

Having now described and pointed out the new and useful features of my invention, I do not limit myself to the shape of certain parts where the shape is not essential, nor do I restrict myself to the exact details of construction shown and described, but mean and intend to claim all equivalents and variations thereof not departing in principle from my invention, and falling within the purview of the appended claims.

What I claim as my invention and desire to secure by Letters Patent is:

1. A match safe consisting of a weighted base, a match container removably mounted upon said base, said container formed with an upwardly extending opening in the top thereof, an igniting material mounted interiorly of said opening, said container formed with a vertical slot through the front face thereof, elevating means slidably mounted within said slot whereby matches will be ejected through said opening, and means mounted within said container for maintaining the matches therein in opera-

tive position with respect to said elevating means.

2. A match safe of the character described consisting of a base, a casing slidably mounted upon said base, the front wall of said casing extending above the upper marginal edge of the casing, a cover member mounted upon said casing and having the forward end thereof upturned and spaced apart from the front face of said casing, igniting paper mounted upon said casing and adapted to form a lining for the interior walls of said front face and said upturned portion of said cover, a match container mounted within said casing and provided with horizontal slots near the upper edge thereof, a spring actuated flange follower plate mounted within said container and slidably mounted within said slots, and means slidably mounted within said casing and said container for ejecting a plurality of matches.

3. A match safe of the character described consisting of a base, a casing slidably mounted upon said base and provided with a vertically disposed slot in the front face thereof, a cover pivoted to said casing and having the forward end thereof upturned to form the rear wall of a match withdrawal aperture, a match container mounted within said casing provided with horizontal slots near the upper edge and a vertical slot in the front face thereof, a spring actuated flanged follower mounted within said container and slidably engaged with said horizontal slots, means slidably mounted within said vertical slot adapted to eject a plurality of matches through said withdrawal opening, and means mounted upon said casing and forming a lining for said withdrawal opening whereby the matches will be ignited upon withdrawal therefrom.

4. A match safe consisting of a base, a casing mounted upon said base, provided with a vertical slot disposed in the front face thereof, a cover hingedly mounted upon the casing and having the forward end thereof upturned to form the rear wall of a match withdrawal aperture, a match container mounted within said casing provided with a vertical slot in the front face thereof registering with the first vertical slot, the bottom plate member of said container having a portion removed, a handle ejecting means, a follower mounted upon springs to provide closure means for the said opening in the bottom plate member when the operating handle is raised.

In testimony whereof I affix my signature hereto.

PETER S. LEKAS.
